DESIGN.

—o—

T. B. WAY.

STOVE DOOR.

No. 16,753.

Patented June 22, 1886.

UNITED STATES PATENT OFFICE.

THEODORE B. WAY, OF TROY, NEW YORK, ASSIGNOR TO W. STONE SMITH,
OF SAME PLACE.

DESIGN FOR A STOVE-DOOR.

SPECIFICATION forming part of Design No. 16,753, dated June 22, 1886.

Application filed April 28, 1886. Serial No. 200,484. Term of patent 3½ years.

To all whom it may concern:

Be it known that I, THEODORE B. WAY, of the city of Troy, county of Rensselaer, State of New York, have invented and produced a new and useful Design for the Ash-Pit Doors of Stoves, of which the following is a specification.

My design relates to the exterior form of stove ash-pit doors, as the same is shown in the accompanying photograph, forming a part of this specification, and in which the main or body part of the door is designated at D with it as having its exterior surfaces mainly in the same plane. The letter H designates a hood that is arranged on the exterior and at the front of the body part of the door. This hood, from where applied to the body part of the door and at its top, curves downwardly and frontwardly to form a curtained part of the hood, as indicated at h², and the ends of the hood from where attached to the body part of the door curve outwardly and frontwardly to join the curtained part, as indicated at h³. The curtained part of the hood is continued down to a point a little below the transverse center of the body part of the door. The bottom edge

of the curtained part is molded, as indicated at m', and has the centrally-placed pendent ornament O. The inner edges of the frontwardly-projected end parts of the hood are curved and molded, as designated at m'; but, if desired, the moldings m' m' and the ornament O may be omitted, provided the combined body part and hood have the same general form.

Having thus described my design, what I claim, and desire to secure by Letters Patent, is—

The design for a stove ash-pit door, consisting of the body part D, having its exterior surfaces mainly in the same plane, and the hooded part H, outwardly and frontwardly projected from the body part, as shown and described.

Signed at Troy, N. Y., this 24th day of March, 1886, and in the presence of the two witnesses whose names were by them hereto written.

THEODORE B. WAY.

Witnesses:

GEO. A. DARBY,
CHARLES S. BRINTNALL.
